**COIL HAVING HEAT CONDUCTIVE SEGMENTS
AND C-SHAPED CONDUCTIVE PATH**

Alvar P. Wilska, Tucson, Ariz., assignor to Philips Electronics and Pharmaceutical Industries Corp., New York, N.Y., a corporation of Maryland

Filed July 5, 1962, Ser. No. 207,707

2 Claims. (Cl. 336—61)

This invention relates to an electrical coil for producing a concentrated magnetic field. In particular, it relates to a coil suitable for use in electron beam focusing devices and not requiring ferromagnetic material to concentrate the magnetic field.

It is frequently desirable to produce strong magnetic fields in concentrated spaces, particularly in devices making use of electron beams, such as electron microscopes and traveling wave tubes and the like. It has long been known that magnetic fields may be produced by the passage of an electric current through a conductive coil and that such fields can be concentrated or shaped to a limited extent by shaping the coil itself. However, it has been thought heretofore that, in order to have a very highly concentrated magnetic field produced by current flowing through a coil, the coil would have to be wound on, or associated closely with, a ferromagnetic core structure.

In certain electron beam devices, particularly electron microscopes, the inhomogeneities of a ferromagnetic core structure introduce distortions in the magnetic field that result in unacceptable distortions of the beam. These inhomogeneities are at least partly determined by the crystalline structure of the ferromagnetic material and are not systematic and cannot be completely corrected.

Furthermore, hysteresis effects in ferromagnetic material makes it difficult to control variations in the magnetic intensity to the precise amount that is frequently required. One reason is that the hysteresis effect results in a non-linear variation of the magnetic field, even if the electric current in the associated coil can be varied linearly. For another thing, the domains of the ferromagnetic particles shift abruptly. In addition, the non-linearity is made worse by the fact that ferromagnetic materials become saturated when the magnetic flux exceeds a certain amount, depending on the volume of ferromagnetic material involved.

The present invention comprises a coil capable of producing highly concentrated magnetic fields without ferromagnetic material. The coil is made up of individual, conductive layers each of which is in the form of a conductive sheet with an almost-closed circuit surrounding an inner non-conductive, or open, space. The edges of the sheet extend outwardly from the circuit and are formed integrally therewith by means of slots extending from the edge of the sheet in toward the circuit. Any number of these layers may be stacked together, but they must be insulated from one another, and also in accordance with the present invention, this insulation may be in the form of a thin layer of material, such as evaporated silicon dioxide. In order to connect the layers together, a limited area at the end of the circuit on one side of the sheet is kept free of insulating material and is covered instead with solder or the like so that the layers may be stacked together and heated simultaneously to cause the solder at one end of each circuit to become attached to the other end of the circuit of the next adjacent layer.

The invention will be described in greater detail in connection with the drawing, in which:

FIG. 1 shows a single layer of a coil constructed according to the invention;

FIG. 2 shows an enlarged cross-sectional view of the layer in FIG. 1 taken along the line 2—2;

FIG. 3 shows an enlarged cross-sectional view of a stack of such layers; and

FIG. 4 shows a coil constructed in accordance with FIG. 3 expanded axially.

The coil layer in FIG. 1 comprises a sheet 11, which in this case is a circular sheet of conductive material, such as copper. The sheet may have any desired thickness; in a particular embodiment, I have used a sheet having a thickness of approximately 2 mils. The sheet has a C-shaped, conductive path or circuit 12 defined by an open inner area 13 and, less explicitly, by the inner ends of a plurality of slots 14 spaced around the sheet. The slots 14 may be spaced at approximately equal angles, although this is not necessary, and normally they extend approximately radially in toward the center of the area 13.

In order to define a conductive path 12, the slots 14 extend only part way from the edge of the sheet 11 toward the open area 13. However, one slot 16 extends all the way in to the open area to give the conductive path 12 a C-shaped configuration so that it will not be self short-circuiting. Electrical connections may be made to the path 12 by means of the segments 17 and 18 lying on each side of the slot 16.

Alternatively, and particularly if a number of sheets, such as sheet 11, are to be connected together, a small area 19 at one end of each conductive path 12 on each of the sheets may be provided with a conductive material, such as a low melting point solder, to permit the sheets to be stacked together and then heated to melt the solder on each layer to make it adhere to the adjacent layer. Preferably, a limited solder area 21 is also provided on the other side of the sheet 11 at the other end of the conductive path 12.

In order to stack a multiplicity of sheets 11 together, or even to permit a single sheet to be attached to a conductive body, it is desirable to insulate the surface of the sheet. FIG. 2 shows a layer of insulating material 22 on the surface of the sheet 11. In the example referred to above of a 2-mil sheet 11, it was found that a layer of evaporated silicon dioxide approximately 10 microns thick was sufficient to insulate the copper.

In order to connect the sheets together electrically, the insulating material 22 must be kept off of, or removed from, a limited area at one end of the C-shaped path 12 (FIG. 1). This may be done by masking a small area of the sheet 11 at the time the insulating material is applied and then later removing the mask and applying a small amount of metal that melts at a low temperature. For example, a small quantity of tin may be evaporated onto the area 19.

When a plurality of sheets 11 is to be connected together in a stack, as indicated in FIG. 3, it is necessary to arrange the sheets so that the low-melting-temperature metal at one end of the conductive C-shaped path of one sheet will join with the low-melting-temperature metal at the other end of the next adjacent sheet. This is indicated in FIG. 3 by the junction between the area 21a of sheet 11a, which is directly in contact with and is fused to the area 19b of sheet 11b. Upon reflection it will be apparent that the points of contact are not in a straight line and therefore in the two sheets 11c and 11d at the other end of the stack the corresponding areas 21c and 19d are angularly displaced from the areas 21a and 19b.

FIG. 4 shows an expanded spiral made up of a number of sheets corresponding to sheet 11. Normally, of course, the layers of such a spiral would not be spread apart; this is done here only for illustrative purposes. As may be seen, the slots 14 of the various layers need not be aligned with one another, so that the whole stack forms something approaching a monolithic conductive block which serves as an excellent heat conductor to carry heat away

from the area where the electrical current is flowing, i.e. in the inner C-shaped path 12 of each layer. Because of the integral formation of the conductive path 12 and the outer segments of each sheet, these outer segments are well adapted to serve as cooling fins to carry heat away from the conductive path portion 12. However, the electrical current will not flow across the slots 14 and is, therefore, confined substantially entirely to the conductive path 12. Even if the current fringes slightly into the outer segments, it will not adversely affect the shape of the magnetic field to any significant degree and may be easily compensated for.

In the case of a 90-layer coil made up of 2-mil sheets, I have found it possible to obtain a 5 mm. focal length in an electron beam accelerated to 10,000 volts with a temperature rise in the coil of only approximately 4° C. above ambient temperature, even though the heat radiated by the coil amount to 36 watts. The number of ampere turns was 1,000. The same coil operated with a beam accelerated to 90,000 volts, and with the coil's dissipating 108 watts with 3,000 ampere turns, had a temperature rise of only approximately 12° C. above ambient temperature.

While this invention has been described in terms of a particular embodiment, it will be recognized by those skilled in the art that modifications may be made therein without departing from the true scope of the invention as defined by the following claims.

What is claimed is:

1. A coil comprising a plurality of turns, each of said turns comprising a circular sheet of conductive non-ferromagnetic material having a central aperture therein; a first slot extending from the edge of said circular sheet to said aperture; a plurality of other V-shaped slots extending from the edge of said sheet part of the way in toward said aperture, said other slots being spaced substantially equi-distantly around said sheet and leaving a C-shaped, conductive path surrounding and defining said aperture with the ends of said C-shaped, conductive path bounding and defining the innermost ends of said one slot; a first

solder layer in a limited region at one end of said C-shaped, conductive path on one surface of said sheet; a second solder layer in a second limited region on the other surface of said sheet at the other end of said C-shaped, conductive path; and an insulating layer intimately attached to and covering both surfaces of said sheet except for each of said solder layers, the first solder layer of each of said turns being fused to the second solder layer of the adjacent turn, said turns being in surface-to-surface contact to form a monolithic, hollow air-core coil.

2. A coil comprising a plurality of turns, each of said turns comprising a circular sheet of conductive non-ferromagnetic material having a central aperture therein; a first slot extending from the edge of said circular sheet to said aperture; a plurality of other V-shaped slots extending from the edge of said sheet part of the way in toward said aperture, said other slots being spaced substantially equi-distantly around said sheet and leaving a C-shaped, conductive path surrounding and defining said aperture with the ends of said C-shaped, conductive path bounding and defining the innermost ends of said one slot; a first solder layer in a limited region at one end of said C-shaped, conductive path on one surface of said sheet; a second solder layer in a second limited region on the other surface of said sheet at the other end of said C-shaped, conductive path; and a layer of evaporated silicon dioxide intimately attached to and covering both surfaces of said sheet except for each of said solder layers, the first solder layer of each of said turns being fused to the second solder layer of the adjacent turn, said turns being in surface-to-surface contact to form a monolithic, hollow air-core coil.
